UNITED STATES PATENT OFFICE

2,447,891

PIVOTED BREECH BLOCK PISTOL WITH A
THREE-PRONGED BIASING SPRING

John Basil Arrowsmith, Aston, Birmingham, England, assignor to Accles & Shelvoke Limited, Aston, Birmingham, England

Application November 23, 1944, Serial No. 564,783
In Great Britain November 23, 1943

9 Claims. (Cl. 42—34)

1

This invention has reference to pistols and has particular reference to pistols for use in stunning animals preparatory to slaughtering.

One object of the invention is to provide a pistol which can be taken to pieces easily and quickly to enable access to be obtained to the working components of the firing and extractor mechanisms.

Another object of the invention is to provide a pistol having firing and extractor mechanisms to which access can be obtained and which mechanisms can be removed easily and quickly for cleaning, replacement or other maintenance purposes.

Another object of the invention is to ensure that, if any of the component parts of the pistol is assembled incorrectly, the final assembly of the pistol cannot be carried out.

Still another object of the invention is to ensure that the means for extracting a spent cartridge from the barrel of the pistol may be actuated automatically and with certainty by movement of a breech block after each shot has been fired.

Yet another object of the invention is to provide a special spring for loading various operating components of the firing and extractor mechanisms and to ensure that such spring can be fitted only in its correct predetermined position and cannot become unduly slack by inadvertance.

It is also an object of the invention to provide a device for locking any assembly bolts, pins or studs securely, quickly and easily in the pistol body so that they also cannot become slack or be removed inadvertently.

Further objects of the invention will be apparent from the following description which is made with reference to the accompanying drawings.

In the drawings, which show a pistol for use in stunning animals preparatory to slaughtering:

Figure 1 is an elevation showing the pistol of my present invention in its normal or fired position.

Figure 2 is a sectional elevation of Figure 1.

Figure 3 is a similar view to Figure 1, but shows the safety action between the hammer and breech block.

Figure 4 is a similar view to Figure 2, but shows the hammer fully cocked and the extractor about to be released from the breech block.

Figure 5 is a section on the line A—A, Figure 1.

2

Figure 6 is a sectional elevation of the barrel portion of the pistol showing the same detached from the grip portion of the pistol.

Figure 6a is a sectional elevation of the grip portion of the pistol showing the same detached from the barrel portion of the pistol.

Figure 7 is an elevation and Figure 7a is a plan, on an enlarged scale, of the spring for actuating various parts of the mechanism which are carried in the barrel portion, and

Figure 8 is an elevation of a device for locking the barrel portion and grip portion in their assembled relationship.

The pistol consists of a barrel portion 1 and a grip portion 2, said two portions being retained in their assembled relationship by bolts 3 and 4. The bolts 3 and 4 are secured by nuts 5 which are themselves locked against movement by a plate 6 carried on one side of the barrel portion 1 and having an aperture and a recess which fit around or against the nuts 5.

The barrel portion 1 comprises the barrel 7, in the breech end of which a block 8 is removably housed, and integral depending side cheeks 9 between which a breech block 10, an extractor 11 and a hammer 12, are journalled.

The breech block 10 is cut away or recessed, at 10b, at its underside and is provided in the said recess with a sleeve 14 which sockets on to, and is rotatable around, a pin 13 extending between, and removably mounted in, the side cheeks 9 of the barrel portion 1. The extractor 11 is rotatably mounted upon the said sleeve and is formed on its underside with a jaw or notch 17; the said extractor is also provided with a toe 18 which projects forwardly or muzzlewards of the said jaw 17. An extractor-operating pawl 15 is pivotally mounted at one end upon a pin 15b in the recess 10b and at the heel 10a of the breech

block rearwardly of the extractor. The said pawl 15 is located in the plane, and projects below the underside, of the extractor 11 and is provided on its upper edge with a tooth 16 which, when the pistol is in its normal or fired position, engages with the extractor jaw 17. The arrangement is such that, as the breech block 10 is turned about the pin 13 away from the block 8, the pawl 15 is moved bodily forwardly or muzzlewards and actuates the extractor. A stud 18 extends through

one of the side cheeks 9 of the barrel portion 1 into the path of an inclined nose 15a formed on the free end of the said pawl 15 and as the latter is moved bodily forwardly or muzzlewards by the pivoting movement of the breech block 10 away from the block 8, the said nose abuts against and

travels under the stud 18; the pawl is thereby depressed about its pivot pin 15b in the heel of the breech block 10 to take the tooth 16 gradually out of engagement with the jaw 17.

Two flat or substantially flat faces 21 and 22 are formed on the lower journalled end of the breech block 10, the said faces being disposed at right angles to one another, and, together with the arcuate union between their adjacent ends, are adapted for engagement by a spring for retaining the breech block 10 resiliently in any of its alternative positions. The breech block 10 also slidably accommodates the firing pin 23.

The hammer 12 is journalled upon, and extends below, a separate pin 19, the lower end of said hammer being bifurcated and each bifurcation thereof being slotted longitudinally as at 20.

Lugs 24 and 25 are provided respectively on the front of the hammer 12 and the rear of the breech block 10 and serve as a safety device when the breech block 10 is withdrawn from its face to face contact with the block 8.

The grip portion 2 of the pistol comprises the handle 26 and a superimposed platform 27, the latter being formed with a lug 28 at its forward or muzzle end and another lug 29 at its rear or breech end, the said lugs 28 and 29 being adapted to make a close fit between the side cheeks 9 of barrel portion 1, and to receive the assembly bolts 3 and 4.

Slidably carried upon the platform 27 is a sear rod 30, the rear or breech end of which is pivotally connected to the bifurcated end of the hammer 12 by a cross pin 31 engaging the slots 20, whereas the forward or muzzle end of the rod 30 extends into a hole 32 in the lug 28 and is formed with a hook-like nose 33 adapted to engage the tooth 34 of the trigger 35. A collar 36 is fixed upon the sear rod 30 and is adapted to ride along the upper surface of the platform 27 for maintaining the rod in its correct alignment when the pistol is cocked or fired. A coil spring 37 is carried around the rod 30 and is compressed between the lug 28 and the collar 36.

The trigger 35 is assembled in a slot 38 formed in the lug 28, and is pivotally mounted on a pin 39 which is retained in position by the cheeks 9. A spring loaded plunger 40 housed within the forward or muzzle end of the platform 27, abuts against the trigger below its pivotal mounting and tends to turn the trigger in the direction which takes the tooth 34 thereof towards the hole 32 so that the tooth 34 engages the hooked nose 33 of sear rod 30 automatically when said sear rod is taken into the slot 38.

A three-pronged spring 41 is mounted on the lug 28 of platform 27 by a screw 42. This spring consists of a single length of wire and is formed with an eye 43 for receiving the shank of a screw 42. The head of the latter is of such a depth that, when the pistol portions 1 and 2 are in their correct assembled relationship, the crown of screw 42 abuts, or closely abuts, the underside of the barrel 7 so that the said screw cannot be slackened inadvertently, for example, by the shocks or vibrations resulting from the firing of the pistol, and allow the spring 41 to become loose upon the lug 28.

The spring 41 comprises three prongs 44, 45 and 46, which extend from the lug 28 towards the rear or breech end of the platform 27 and bear, respectively, against the breech block 10, the extractor 11 and the pawl 15. The central or extractor prong 45 of spring 41 is formed by

folding the wire upon itself and by coiling each portion of the fold upwardly, as at 47, before one side merges into the lateral or pawl prong 46, and the other side merges into the eye 43 and from the eye into the other lateral or breech block prong 44. The breech block and pawl prongs 44, 46, respectively, are so spaced apart that, when the pistol portions 1 and 2 are assembled, said prongs are located close to the adjacent cheeks 9. The eye 43 of spring 41 is offset relatively to the longitudinal centre line of the complete spring so that unless the said spring is correctly assembled to the lug 28 with the coils 47 uppermost, it is impossible for the said prongs 44 and 46 to pass between the cheeks 9. The heel of the pawl prong 46 is located below the level of the eye 43 and is adapted to abut against the lug 28. Hence, as the screw 42 is screwed down, the prongs of the complete spring cannot be taken inadvertently out of alignment with the components 10, 11 and 15, against which they are required to bear, due to the final tightening of the screw 42.

Further, the diameter of the coils 47 is such that they are adapted to bear against the underside of the barrel 7 and, therefore, are unable to move upwardly when the central extractor prong 45 is stressed upwardly by the turning movement of the extractor 11 under the action of the pawl 15 and, hence, the said prong 45 can operate without affecting the operation of the two lateral prongs 44 and 46.

The breech block prong 44 presses against the underside of the breech block 10 against one or other of the straight edges 21, 22, or against the convex arcuate junction therebetween, and serves for retaining the said breech block resiliently in any position in which it is set, the retention being more secure when the prong 44 engages one of the said edges 21, 22. The central prong 45 bears upon the upper edge of the toe 48 which projects forwardly or muzzlewards from the extractor 11 and the prong 46 bears on the underside of the pawl 15 and tends to retain said pawl tooth 16 in engagement with the extractor jaw 17.

The nut-locking plate 6 has a lever 49 hinged thereto adjacent its forward or muzzle end. The plate 6 is formed with apertures 50 and 51 through which the stud 18 and the hammer spindle 19 project. A jaw 52 is formed in the upper edge of the plate 6 and the spindle 13 carrying the extractor 11 and breech block 10 extends therethrough.

The head of the stud 18 is formed with a peripheral groove (see Figure 5), and the ends of the spindles 13 and 19 are formed with peripheral grooves (not shown), these grooves in the ends of said stud and spindles being adapted for engagement by jaws or notches 53, 54, and 55, respectively, provided in the upper edge of the lever 49 when the latter is swung into overlapping relationship to the plate 6 for positively retaining the said stud 18 and spindles 13 and 19 against longitudinal movement in the cheeks 9. For retaining the lever 49 in its overlapping relationship to the plate 6, the latter is formed with holes or depressions 56 which are adapted to be engaged by complementary protuberances 57 from the underside of the lever 49, and this engagement is such that it can be broken only by some suitable tool being applied to an ear 58 on the lever 6 and levering the tool about the nut 5 or some other fulcrum point on the pistol.

To load the pistol, the hammer 12 is cocked

by hand from the position shown in Figure 1 to the position shown in Figure 4. During this operation, the sear rod 30 is slid forwardly or muzzlewards by the bifurcated end of the hammer 12; the spring 37 is compressed; and the hook-like nose 33 of said sear rod is engaged by the trigger tooth 34, thus retaining the rod 30 and hammer 12 in their cocked position.

The breech block 10 is then hinged away from the block 8, again by hand, to a position beyond that shown in Figure 4, when a cartridge may be inserted into the block 8. During this operation, the pawl 15 is driven forwardly or muzzlewards so that, during the initial movement, the extractor 11 travels automatically with the breech block 10. As the pawl 15 moves, its nose contacts and then rides under the stud 18 and it is turned about its pivot pin, against the spring prong 46 and the tooth 16 is gradually withdrawn from engagement with the extractor jaw 17 until, as shown in Figure 4, the engagement is severed and the extractor 11 is returned automatically to its initial position against the block 8 by means of the spring prong 45. Thus, when the cartridge is inserted into the block 8, the rim around its head is able to engage behind the recessed free end of the extractor 11.

Before the cartridge can be fired, it is necessary to return the breech block 10 to its initial position. Otherwise the release of the hammer 12 by pulling the trigger 35, causes the lug 24 to strike the breech block 10 above the lug 25 thereon and to engage the latter and lock the breech block 10 and hammer 12 in the safety positions shown in Figure 3.

If, however, the breech block 10 has been returned previously to its initial position against the block 8, thereby enabling the pawl 15 to be re-engaged with the extractor jaw 17, the releasing of the hammer 12 enables the latter to be driven by the compressed spring 37 against the firing pin 23 to explode the cartridge in block 8. The empty cartridge in block 8 is removed automatically from the block 8 by the extractor 11 when the breech block 10 is again hinged away from the block 8.

Should any of the mechanism require attention such as repair, replacement or maintenance, it is only necessary to remove the lever 49 from its overlapping relationship with the plate 6; disengage the latter from the nuts 5; and unscrew the said nuts, whereupon the bolts 3 and 4 may be removed to enable the grip portion 2 to be withdrawn from the barrel portion 1. The hammer 12, breech block 10 and extractor 11 are then no longer under spring action and may be disassembled from the barrel portion 1 merely by removing the pins 13 and 19. Or, if desired, the said pins 13 and 19 may be removed prior to separation of the portions 1 and 2. The separation of the portions 1 and 2 also exposes the triple purpose three-pronged spring 41, and permits of the ready removal of the said spring-fastening screw 42. As the sear rod 30 is no longer anchored at its rear or breech end, it and the spring 37 may be removed from the platform 27 merely by raising the rear or breech end of the rod.

The various components of the pistol may readily be replaced since, insofar as the breech block 10, extractor 11 and hammer 12 are concerned, they are free from spring action when the portions 1 and 2 are separated, and the sear rod spring 37 has to be compressed only to a slight degree.

To reassemble the pistol portions 1 and 2,

after the breech block 10 and extractor 11 have been replaced and engaged by their pin 13 (the grooved end of which remains projecting to the outside of the side cheek 9 carrying the stud 18), it is preferable that the hammer 12 should not be replaced in the barrel portion 1 and that the sear rod 30 should be actuated against its spring 37 into engagement with the trigger 35. The barrel portion 1 is then inverted and so held in one hand by the assembler that the breech block 10 and extractor 11 are retained against the block 8.

With his other hand, the assembler inserts the lug 29 of the platform 27 between the cheeks 9, the platform in alignment with the barrel 7 and the spring 41 located forwardly or muzzlewards of the breech block 10, extractor 11 and pawl assembly. Thus by sliding the grip portion 2 to take the other lug 28 between the cheeks 9, the bolt holes in the said lugs 28 and 29 may be brought into the position wherein bolt holes 3a and 3b in the lugs 28 and 29 (see Figure 6a) register with bolt holes 4a and 4b (see Figure 6) in the said cheeks, and the spring prongs 44, 45 and 46 may be brought automatically into contact with the breech block 10, extractor 11, and pawl 15, at the desired positions.

The bolts 3 and 4 may then be inserted through the said registering bolt holes, 3a, 3b and 4a, 4b, until their ends project beyond the side cheek 9 which carries the stud 18, whereupon the said bolts may be secured by the application of the nuts 5 to the said projecting ends; the hammer 12 may be inserted between the cheeks 9 and secured by its pin 19 (the grooved end of said pin also being positioned to project beyond the stud-carrying side cheek 9), the bifurcated end of said hammer being able to engage readily with the cross pin 31 due to the previous locking of the sear rod 30. Finally the locking plate 6 is engaged around and against the nuts 5 and its lever 49 is swung into overlapping relationship therewith to engage the grooves in the pins 13 and 19 and in the stud 18.

Having described my invention what I claim and desire to secure by Letters Patent is:

1. In a pistol, an extractor, a breech block, an extractor-operating pawl rotatably mounted on said breech block, and a one-piece spring comprising at least three prongs, one of which loads the extractor, a second of which loads the breech block, and a third of which loads the extractor-operating pawl.

2. A pistol having an extractor and a breech block with an extractor-operating pawl rotatably mounted thereon, the said breech block having a sleeve around which the extractor is rotatably mounted, and a recess in the underside in which one end of the extractor-operating pawl is rotatably mounted; a triple-pronged spring being mounted within the pistol with one prong loading the breech block, the second prong loading the extractor and the third prong loading the extractor-operating pawl.

3. A pistol having an extractor and a breech block with an extractor-operating pawl rotatably mounted thereon, the said breech block having a sleeve around which the extractor is rotatably mounted, and a recess in its underside in which one end of the extractor-operating pawl is rotatably mounted in the plane of and below the extractor, the said extractor having a jaw in its underside and a toe projecting forwardly of said jaw, and the said pawl having a tooth on its upper edge; a triple-pronged spring mounted in

the pistol forwardly of the breech block with one prong thrusting against the underside of the breech block, the second prong thrusting against the extractor toe and tending to rotate the extractor, and the third prong thrusting against the underside of the extractor-operating pawl and tending to rotate the said pawl to take the pawl tooth into engagement with the extractor jaw.

4. A pistol having an extractor, a breech block and an extractor-operating pawl, said breech block being recessed on its underside and provided, in the said recess, with a sleeve pivotable around a fixed stud, the said extractor being journalled upon said sleeve and the extractor-operating pawl being pivoted at one end in the said recess at the heel of the breech block and projecting below the said extractor, the said extractor having a jaw in its underside and a toe projecting forwardly from the jaw, the said pawl having a tooth on its upper edge and an inclined nose face at its free end, a stud being located in the path along which the said nose is moved by the breech block when the said breech block is pivoted away from the breech of the pistol, a triple pronged spring being mounted in the pistol with one prong thrusting upon the underside of said breech block, the second prong thrusting upon the top of the extractor toe and tending to turn the extractor away from the breech block, and the third prong thrusting against the underside of the extractor-operating pawl and tending to take the pawl tooth into engagement with the extractor jaw, the said engagement being severed by the said fixed stud as the pawl nose is moved along the said path and its inclined face engages and travels under the said stud.

5. A pistol comprising a pivoted breech block, having a recess in its underside, an extractor, having a jaw in its underside and a toe projecting forwardly from said jaw, rotatably mounted within said recess, an extractor-operating pawl, having a tooth on its upper edge and an inclined nose face at one end and being rotatably mounted at its other end in said recess at the heel of the breech block and projecting below said extractor, the said breech block being formed with a flat face on its underside and its forward edge, a triple pronged spring mounted within the pistol with one prong thrusting against one or other of the said flat faces on the breech block and tending to retain the said breech block resiliently in any position in which it may be set, with a second prong thrusting on the top of said extractor toe and tending to rotate the extractor relatively to said breech block, and with the third prong thrusting against the underside of said pawl and tending to take said pawl tooth into engagement with said extractor jaw to prevent said relative rotation of said extractor, and a stud rigidly mounted within the pistol in the path along which said pawl nose is moved when the breech block is moved away from the barrel breech so that the said inclined face engages and rides under said stud to disengage said tooth from said jaw against the action of said third prong.

6. A pistol comprising a barrel portion in which there are journalled an extractor and a breech block with an extractor-operating pawl rotatably mounted thereon, and a grip portion detachably assembled to said barrel portion and having a platform at its end assembled to said barrel portion and a lug at the forward end of the said platform, a one piece spring being fixed to the

5 crown of said lug, said spring comprising two prongs one of which loads the extractor whereas the other loads the breech block, and a third prong located at a lower level than the said two prongs and loading the extractor-operating pawl, the said third prong being formed with a heel which abuts the side of the said lug laterally of the spring fixing.

7. A pistol comprising a barrel portion in which there are journalled an extractor and a breech block with an extractor-operating pawl rotatably mounted thereon, and a grip portion constructed and arranged to be detachably assembled to said barrel portion and having a platform along its end to be assembled to said barrel portion, a lug being provided at the muzzle end of said platform and a one-piece spring being fixed to the crown of the said lug, the said spring comprising three prongs one of which is arranged to load the breech block, a second is arranged to load the extractor and the third is arranged to load the extractor-operating pawl, and a fixing eye which is off-set relatively to the longitudinal centre line of the spring to prevent assembly of the said pistol portions should the spring be fixed incorrectly to said lug.

8. A pistol comprising a barrel portion having depending lateral side cheeks between which there are journalled an extractor and a breech block with an extractor-operating pawl rotatably mounted thereon, and a grip portion constructed and arranged to be detachably assembled to said barrel portion between said cheeks and having a platform along its end to be assembled to said barrel portion, a lug being provided at the muzzle end of said platform and a one-piece spring, formed at one end with an eye which is off-set relatively to the longitudinal centre-line of said spring, being fixed to the crown of said lug by a screw passing through said eye and engaging said lug, the said screw having a head of a depth such that it closely abuts the underside of the barrel portion when the said portions are in their assembled relationship, and said spring comprising three prongs one of which is arranged to load the breech block, a second is arranged to load the extractor and the third, which is disposed below the level of the said breech block and extractor loading prongs and is formed with a heel which abuts the said lug laterally of the centre of the said fixing eye, is arranged to load the extractor-operating pawl.

9. A pistol comprising a barrel portion having depending lateral cheeks between which there are journalled an extractor and a breech block with an extractor-operating pawl rotatably mounted thereon, and a grip portion constructed and arranged to be detachably assembled to said barrel portion between said side cheeks and having a platform along its end to be assembled to said barrel portion, a lug being provided at the muzzle end of said platform and a spring, made from a single length of wire and formed at one end with an eye which is off-set relatively to the longitudinal centre line of said spring, being fixed to the crown of said lug by a screw passing through said eye and engaging said lug, the said spring comprising three prongs, one lateral prong being arranged to load the breech block, the central prong being arranged to load the extractor and being formed by two portions of the wire located side by side each portion being formed with an upwardly extending coil which bear on the underside of the barrel portion when the said pistol portions are in their assembled

relationship, whereas the other lateral prong is arranged to load the extractor-operating pawl, is located at a lower level than the said breech block and extractor loading prongs, and is formed with a heel which abuts the side of the said lug laterally of the centre of said fixing eye. 5
